Primary Examiner—Selina Sikder

(57) **CLAIM**

The ornamental design for a anode and cathode assembly, as shown and described.

DESCRIPTION

FIG. 1 is a sectional view of the anode and cathode assembly taken along line 1—1 in FIG. 3 wherein the broken lines shown are for illustrative purposes only and form no part of the claimed design;

FIG. 2 is a front view thereof; and,

FIG. 3 is a top plan view thereof, the bottom view being a mirror thereof.
